UNITED STATES PATENT OFFICE.

RALPH J. WEAVER, OF AKRON, OHIO, ASSIGNOR, BY MESNE ASSIGNMENTS, TO NATIONAL RUBBER MACHINERY COMPANY, OF AKRON, OHIO, A CORPORATION OF OHIO.

MOLD.

Application filed March 3, 1926, Serial No. 91,871. Renewed October 10, 1928.

This invention relates to molds especially adapted for the manufacture of battery-boxes from hard rubber or similar compositions.

5 It is one of the objects of the invention to provide a mold structure that will be adapted for the commercial manufacture of battery-boxes, or similar articles, on a commercial scale and at a relatively low cost. A further 10 object of the invention is to provide a mold construction that will be comparatively simple and have its parts so arranged that the articles may be readily removed without liability of breakage. A further object of 15 the invention is to provide a mold structure that will have the necessary steam spaces and suitable provisions for circulating steam about the sides of the mold cavities.

Other objects of the invention and the 20 features of novelty will be apparent from the following description taken in connection with the accompanying drawings of which

Fig. 1 is a plan view of a mold embodying 25 my invention;

Fig. 2 is a horizontal section through the same;

Fig. 3 is a side elevation, on a reduced scale, with certain parts shown in section;

Fig. 4 is a side elevation of the movable top 30 of the mold which carries the cores, certain parts being shown in section;

Fig. 5 is a plan view of the same, on a reduced scale;

Fig. 6 is an elevation of the mold top, as 35 seen from the left side of Fig. 4, certain parts being shown in section; and

Fig. 7 is a transverse section of the mold on the line 7—7 of Fig. 3.

Referring to the drawings, 10 indicates the body casting which is provided with two mold cavities 11 and 12, the body casting having the jacket spaces 13, 14 and 15 in its walls. The upper ends of the jacket spaces are closed by integral walls as indicated at 16 but the 5 lower ends of these jacket spaces extend to the lower side of the casting and merge into the bottom jacket spaces 17. A steel plate 18 is arranged on the bottom of the body casting and covers the jacket spaces, this plate having its periphery welded to the body casting as indicated at 19.

The mold cavities extend to the ends of the body casting and are closed by the end plates 20 and 21 which are hinged, at their lower ends, as indicated at 22. The end

plates 20 and 21 are hollowed out, on their outer sides, to form the jacket spaces 23 and these spaces are closed by means of plates 24 which are welded to the end plates as indicated at 25. The end plates 20 and 21 are also formed with internal ribs 26 which serve to circulate the steam through the spaces 23 in a most effective manner. Ribs 27 are also provided in the jacket spaces 13, 14 and 15 for the purpose of tying the walls of these spaces together and to assist in the distribution of the steam.

Each of the mold cavities 11 and 12 is lined with plates 28, 29, 30 and 31, which are suitably shaped to produce the article desired. 70 The hinged end plates 20 and 21 also carry plates 32 forming one side of the article. The plates 31 are permanently secured in the mold cavities but the plates 28, 29 and 30 are removable, with the article, when the latter 75 is withdrawn. The plates 32, being mounted on the end plates 20 and 21, move with the latter. The plates 29 and 30 are each provided with a recess 33 and the body casting is provided with openings 34, which register 80 with the recesses 33, and permit the insertion of hooks which are adapted to engage with the recesses 33 for the purpose of pulling out the plates 29 and 30, when the end plates 20 and 21 are thrown down to their open position.

Heavy bars 34 and 35 are permanently attached to opposite sides of the body casting 10 and extend beyond the ends thereof. These bars are provided with aligned notches 36 85 adjacent their ends to receive the trunnions 37 of the cam members 38 which are adapted to engage the outer sides of the end plates 20 and 21 for the purpose of securing the latter against the body casting to close the molds. 90 One, or both, of the trunnions 37 of each cam member 38, may be provided with a squared extension 39 adapted to receive a wrench for the purpose of rotating the cam member.

The top of the mold is closed by a plate 40 100 which carries the core members 41 that are adapted to enter the mold cavities and form the cells of the battery-boxes, the spaces 42 between the core members forming the partitions between the cells. The core members 41 have their upper ends arranged in rectangular openings in the plate 40 and secured by means of a wedge 43, blocks 43' being provided between the cores for properly spacing them. Each of the core members 41 is pref- 110

erably made hollow to provide steam spaces into each of which there extends a pipe 44 for the purpose of removing the condensation. Steam may be admitted to the interior 5 of the core members 41 by means of a supply pipe 45 and partitions 46 are provided for the purpose of causing the steam to circulate therein.

The plate 40 has downwardly projecting 10 guide rods 47 which are adapted to enter openings 48 in the bars 34 and 35 for the purpose of properly registering the plate 40 with the body of the mold.

In the operation of the mold it is placed in 15 a press, of the usual type, the plate 40 being bolted to the upper stationary member of the press. The end walls 20 and 21 are closed, and secured by the cam members 38, and the proper amount of material is placed in the 20 mold cavities. The jacket spaces are connected with a steam supply, by suitable pipes, (not shown) and drain pipes are also provided for carrying away the condensation from the jacket spaces, according to usual 25 practice. The plunger of the press is raised to close the top plate 40 against the top of the body casting and to properly position the core members 41 in the mold cavities, this operation forcing the material into all parts

of the mold cavities. The mold is allowed to 30 remain closed for the requisite time to properly vulcanize the material and then the plunger is raised to open the mold and remove the core members 41. The cam members 38 are then rotated to disengage them 35 from the end plates 20 and 21 and are then removed. The end plates are then swung down to the horizontal position as shown in Figure 3, thereby permitting hooks to be inserted in the openings 34' for the purpose 40 of withdrawing the plates 28, 29 and 30 with the article adhering thereto. These plates are then detached from the article and replaced in the mold cavities and the operation 45 repeated.

What I claim is:

In molds, the combination of a main body having a cavity for the article to be molded, and a plunger plate for closing one side of said cavity, said plate having an opening 50 therein, a plurality of cores positioned in said opening and adapted to cooperate with said cavity, and a wedge for securing said cores in said opening.

In testimony whereof, I hereunto affix my 55 signature.

RALPH J. WEAVER.
